PUMP OR MOTOR FOR HYDRAULIC POWER
TRANSMISSION SYSTEMS

Wolfgang C. Muller, Springfield, Vt.

Application August 19, 1930. Serial No. 476,315

REISSUED

9 Claims. (Cl. 103—38)

This invention relates to pumps or motors more particularly designed for use as parts of hydraulic power transmission mechanisms of the general type illustrated in my application for patent Serial No. 333,452 filed January 18, 1929, for Hydraulic variable-speed power-transmitting mechanism, such mechanism including pumps and motors each having moving and eccentric parts. One object of this invention is to provide means for varying the eccentricities of certain of such parts.

A further object is to counterbalance such parts so that no vibration of the mechanism when in operation may be produced.

15 A still further object is to improve the valve structure to lessen flow restriction and to balance pressures thereon.

Another object is to stiffen the casing walls to decrease leakage and make possible lighter construction.

20 Another object is to provide improved means for preventing rotation about its axis of certain of the eccentrically moving members.

A further object is to provide means for freeing and maintaining the hydraulic system free from air and simultaneously cooling it.

Further objects and advantageous constructions will appear from a more complete description of an embodiment of the invention shown 30 in the accompanying drawings in which

Figure 1 is a central vertical section through a pump embodying the invention.

Figures 2 and 3 are sections on lines 2—2 and 3—3, respectively, of Figure 1.

35 Figure 4 is a fragmentary view to a larger scale of a portion of Figure 1.

Figures 5 and 6 are sections on lines 5—5 and 6—6, respectively, of Figure 1.

40 Figures 7 and 8 are fragmentary views to a larger scale of portions of Figures 5 and 6, respectively.

Figure 9 is a section on line 9—9 of Figure 1.

Figure 10 is a detail in perspective.

Figures 11 and 12 are sections on lines 11—11 and 12—12, respectively, of Figure 1.

45 Figure 13 is a view similar to Figure 12, but showing the reversing valve in a different position.

Figure 14 is a detail section showing means for preventing rotation of the impeller.

Figure 15 is a detail section on line 15—15 of Figure 5.

In the drawings the pump unit has been illustrated, although it should be understood that the 55 motor element may be substantially identical

therewith though it will not be necessary in both the motor and pump to employ means for varying eccentricity reversing valve mechanism or mechanism for pumping oil into the low pressure side of the system as will later be described and as illustrated in connection with the pump herein shown.

The pump comprises a casing having end walls 1 and 2 and an intermediate partition 3. The partition and end wall 1 are spaced apart by a substantially ring shaped member 4 and the partition 3 and the wall 2 are spaced apart by a similar but, as shown, thinner ring member 5. All these parts are shown as secured together by means of the bolts 6. The casing thus is provided with a pair of substantially cylindrical chambers. In one of these chambers, as between the wall 1 and the partition 3, is positioned an annular piston member 10 and between the partitions 3 and the wall member 2 is positioned an annular valve plate 11. Extending axially through the casing is a hollow shaft 15.

Where this shaft passes through the piston-containing chamber it may be provided with a squared portion 16 as shown best in Figure 10, 80 provided at one end with an enlarged collar portion 17. Between this collar portion and a flanged collar 18 engaging a cylindrical portion 20 of the shaft adjacent to the squared portion 16 is an annular member 25 shown best in Figure 5 having a central rectangular opening 26. This opening is longer than the transverse dimension of the squared portion 16 to allow transverse adjustment of the member 25 lateral to the axis of the shaft, and it is also sufficiently wider than the squared portion to permit anti-friction bearing rolls 27 to be interposed therebetween. These bearing rolls, however, prevent motion between the shaft and the member 25 at right angles to the transverse motion first mentioned. The ring member 25 is provided with inwardly projecting posts 28 keyed thereto which extend through guiding openings 29 through the squared portion 16 and into contact with means by which the eccentricity of the ring member 25 may be adjusted with relation to the axis of the shaft 15 as will later appear. This ring member 25 has fixed to its periphery the inner raceway member 35 of an antifriction bearing having rolling elements 36 which are arranged to bear between the raceway member 35 and an outer raceway member 37 carried on the inner face of the annular piston 10.

Means are provided by which the space between the piston 10 and the casing ring 4 may 110

be divided into a plurality of expandible and contractible fluid pressure receiving chambers. As shown this means comprises a plurality of partitions as 45, each supported in a rocking bearing 46 in the ring member 4 and slideable between segmental bearing members 47 rockably seated in sockets 48 in the piston member. As the central shaft is rotated this piston member is given a gyratory or orbital movement, causing it to alternately approach and recede from any particular point of the ring 4, thus to cause the chambers 50 between the partition elements, the piston and the ring 4 to alternately increase and decrease in size and progressively angularly around the shaft 15. Each of these chambers has in communication therewith a port 52 extending through a partition member 3. This partition member is also provided centrally with bearings as at 55 for supporting the shaft 15.

20 The means for varying the eccentricity of the piston, as before mentioned, comprises a rod 60 axially slideable through the shaft 15. As shown best in Figure 4 this rod is provided with oppositely disposed faces 61 and 62 arranged in 25 parallel relation and extending at an angle to the axis of the shaft. These faces 61 and 62 are formed to bear on inclined end portions 63 of the post members 28 and in order to reduce friction as much as possible balls 64 are interposed 30 therebetween. Recesses as 65 are formed in the bar 60 into which the pointed ends 66 of the elements 28 may extend when the bar 60 is moved to one or the other of its limits of traverse motion. For example, as shown in Figure 4, the 35 point of the upper bar 28 extends into its recess 65, the bearing ball 64 being at the left hand end of the face 61. When the bar 60 is moved to its extreme left hand position the point 64 of the lowermost bar 28 will likewise extend into the 40 lower recess 65. By moving this bar 60 axially, therefore, it will be seen that the bars 28, and consequently the piston, will be moved transversely to the axis of the shaft, thus to vary the eccentricity of the piston and thereby to vary 45 the extent of size variation of the chambers 50 between their maximum and minimum volumes.

As the eccentric wobbling or gyratory motion of the piston would of itself produce unbalanced forces in the mechanism tending to cause excessive vibration of the mechanism when in operation, means may be provided for counterbalancing such forces. As shown this means comprises a pair of counterbalance weights as 70 and 71. The weight 70 is positioned on the shaft 15 outwardly of the end plate 1 within the recess of which is positioned a bearing 72 for the shaft 15 and the weight 71 is positioned beyond the end wall 2, and as this end wall 2 carries various other mechanisms which will later be described, this 30 weight 71 is positioned axially considerably further from the chamber containing the piston 10 than is the weight 70. In view of this greater distance the weight 71 is made smaller than the weight 70 since it acts through a longer lever 35 arm than the weight 70.

The weight 70, as shown best in Figure 2, is provided with an elongated opening 75 through which the shaft 15 passes so as to permit the weight to be moved transversely of the axis of the shaft. It is shown as provided with a pair of rods 76 adjustably secured as by threaded outer extremities 77 engaging in threaded sockets in the weight 70 and provided with check nuts at 78 to secure them in position and they 75 are also prevented from turning axially as by

means of screws 79, the inner ends of which ride in key slots 80 in the rods 76. The inner ends of these rods are formed inclined to the axis of the shaft and bear with interposed balls 82 against inclined faces 83 on the rod 60 similar to the inclined faces 61 and 62 hereinbefore described, except reversely inclined, so that as the eccentricity of the piston 10 is changed in one direction, the eccentricity of the weight 70 is changed in the reverse direction. The weight 71 is mounted on the shaft 15 similarly to the weight 70 and is arranged to be moved in the same direction simultaneously therewith and opposite to the direction of motion of the piston 10.

Means are provided for shifting the rod 60 axially while permitting it to rotate with the shaft 15 to which it is keyed by the eccentricity adjusting elements 28, 76 etc. extending through openings in the shaft and engaging flattened faces thereof. As shown this means comprises a socket member 90 housing an antifriction bearing 91 on the outer end of the shaft 60 and provided with a closure plate 92 having a central opening through which the rod 60 rotatably extends. This socket member 90, as shown best in Figure 3, is provided with a slotted extremity 94 within which rides a key block 95 in a stationary bearing 96 thus to keep the socket member 90 from rotating with the shaft 15 and the rod 60. Within this slot 94 may be pivoted the inner end of a link 97 connected to an arm 98 of a bell crank lever 99. To the opposite arm 100 of this bell crank lever 99 is attached a rod 101 by which it may be actuated. These arms 100 of this bell crank lever are so angularly related as to produce any desired velocity ratio between the sliding of the rod 60 and the movement of the rod 101 and thus variation in eccentricity with the extent of motion of the rod 101 so as to produce any desired rate of slowing down or speeding up the discharge rate of the pump for a given extent of movement of the rod 101 in various positions. As shown the mechanism is so proportioned as to give a small eccentric adjustment near minimum eccentricity and a larger eccentric adjustment near maximum eccentricity for the same extent of movement of the rod 101 so as to give a finer adjustment at low delivery speeds and in approximately geometric progression which is desirable for lathe spindles. When variable eccentricity in the motor is used this variable control would be reversed.

The valve plate 11 heretofore mentioned is mounted for eccentric orbital movement similarly to the piston 10 except that it is unnecessary to provide for variations in eccentricity. For this reason it is shown as having rotatable in a central opening therein an eccentric 110 secured to the shaft 15 as by means of a key and a nut 111 threaded on a portion thereof and pressing the eccentric against a shoulder 112 on the shaft. This valve plate is arranged with its eccentricity 90° out of phase with the eccentricity of the piston and is counterbalanced by reason of the slot 75 of the counterbalance weight 70 and the similar slot of the weight 71 being arranged sufficiently to one side of the center line of the weights.

It is desirable to provide means for tying the wall members 1, 2 and the partition 3 together inwardly of their separating ring elements 4 and 5. To this end the piston 10 and the valve plate 11 may be provided with circular openings 120 through which may be extended tie bolts such as 125

- 121 between the end plate 1 and partition 3 through the piston 10 and bolts 122 extended through the end plate 2 and the openings through the valve and threaded into the partition 3. These bolts may be provided with collars 123 journaled thereon which may make rolling contact when the piston is of maximum eccentricity with the inner walls of their respective openings in the piston or valve plate, each of these bolts 10 with its collar contacting with one side of the opening through which it passes during one angular position of the gyroratory member and holding this member against rotation about its own axis.
- 15 In order to further control the motion of these members effective through the entire range of eccentric adjustment I have found it desirable to employ short shafts as 125, three being shown extending through and journaled in the partition 3 and provided at their ends with crank pins 126 and 127 which are journaled in suitable openings in the piston 10 and the valve plate 11, respectively. In order to provide for the eccentric adjustment of the piston 10 eccentric adjustment between each crank pin 126 and its shaft 125 must be provided and this may be done conveniently by groove and tongue connections as at 128 between these parts which permit such relative motion. Similar tongue and groove connections are shown as placed between the shaft 125 and the crank pin 127 for the valve plate which permits the parts to adjust themselves to any inaccuracies of manufacture so that extreme accuracy in their manufacture and assembly is not required. This construction is shown in detail in Figure 14.
- 40 The end plate 2 outwardly of the valve member is shown as provided with a pair of concentrically arranged passages 140 and 141. The passage 140 leads out through the inner face of the end plate 2 through a series of ports 142 into the valve chamber and the passage 141 leads into the valve chamber through another series of ports 143 inwardly spaced and concentrically arranged relative to the ports 142. Through the outer face of the end plate 2 the passage 140 is provided with a single port 145 and the passage 141 is provided with a single port 146. These ports 145 and 146 both open into a valve chamber 148 (see Figures 55 12 and 13), within which is shown positioned an oscillatory valve having an actuating shaft 150 secured thereto. The valve casing 148 has communicating therewith a pair of ports 152 and 153 with which may be joined pipes as 154 leading to opposite sides of the motor of the hydraulic system. Either of these ports 152 and 153 may be connected at will with either of the ports 145 and 146. As will later appear the port 145 may be a high pressure port and the port 146 a low pressure or intake port for the pump. By connecting the port 145 to the port 153 as in the position of the valve shown in Figure 13, the fluid under pressure passes through the port 153, the motor, and back through the port 152 to the lower pressure side 65 of the pump. If the valve member 149 is thrown to the dotted line position in Figure 13, the high pressure fluid is led out through the port 152, through the motor in the reverse direction, back through the port 153 and the port 146 to the intake 70 side of the pump. In the position shown in Figure 12 both the ports 152 and 153 are blanked so that the motor is cut off from the pump and the ports 145 and 146 are in open communication with each other so that the pump merely circulates the liquid through these ports. It will be seen by
- reference to Figures 12 and 13, the valve 149 has an extension 160 having an opening in registry with the port 146, a strengthening web 161 being shown as extending across the valve but without blocking off its connection to its upper hollow portion 162 through which the port 145 may be connected to either of the ports 152 or 153 when the valve is swung to proper position. The discharge is around the outside of the valve as will be seen from an inspection of Figure 13. The outer portion of the valve chamber is closed off as by means of a cover plate 165 through which the valve actuating shaft 150 passes, the valve being slideable between this cover plate and the plate 2.
- 80 Means are also provided by which any air which may become entrained in the liquid in the system is removed therefrom and by which any leakage of fluid is made up and by which the liquid is cooled. To this end a fluid supply tank 170 may be provided, as shown in Figure 1, and this tank 85 may act as a support for the pump mechanism, the bearing 96 for the delivery capacity regulating mechanism being shown as integral with one wall thereof and a top wall 171 thereof being shown as supporting the pump casing and having 90 an upwardly extending flange 172 which may be engaged by one or more of the bolts 6 by which the casing is held assembled.
- 95 At 180 is shown a gear pump supported at the lower end of a foot 182 so as to extend below the 100 level of liquid in the tank 170. This foot 182, besides housing the pump gears, also houses a vertical operating shaft 183 therefor, which on its upper end has a spiral gear 184 fixed thereto meshing with spiral gear teeth 185 cut into the shaft 15. 105 The foot 182 is shown as supported in position by a bracket member 186 made fast to the outer face of the wall member 2, as by the screws 188. An intake pipe 190 leads from a suitable point in the tank, preferably remote somewhat from the pump, 110 and a discharge pipe 193 leads from the pump 180 and opens into the low pressure passage 110 in the plate 2. Thus liquid is constantly supplied to the low pressure side of the pump. Any excess liquid which raises the pressure in this low pressure to 115 an undesirable degree is allowed to escape through a relief valve shown at 194 above the pipe 193 and seated in a suitable valve chamber shown as formed integral with the cover plate 165. This valve is pressed to its seat as by a spring 195, reacting against a plug 196 threaded into the valve casing, an exhaust port 198 for the liquid through which it may escape into the tank 170 being provided. The high pressure passage 140 may also be provided with a relief valve as 200 similarly 120 mounted to the valve 194 and having a relief passage 201 communicating with the relief passage 198. The supply of liquid to the pump is preferably taken from a point remote to that receiving the escape past the relief valves since the 125 liquid so escaping may contain air and be in a heated turbulent and somewhat frothy condition due to the churning it receives in going through the system. The intake for the pump 180 is therefore positioned to take the oil after it has 130 had a chance to become settled and cool and to have lost any air which might be contained therein and has full opportunity to mix with the oil already in the pump before it can reach the relief valve 198. This pump 180 therefore produces a 135 discharge through the relief valve which removes the air from the system therewith.
- 140 It is desirable to balance the pressure on opposite sides of the valve plate in order to reduce friction in its operation. To this end the plate 145 150

2 is provided with recesses 220 opposite to the ends of the ports 52 through the partition 3 and the valve plate is provided with openings therethrough as at 225 which permit the fluid under pressure in the ports 52 to pass through the valve plate and exert a pressure on the opposite side thereof, balancing the pressure due to pressure in the ports 52. Inwardly of these openings 225 the valve plate is provided with 10 exhaust openings 230 which register with the low pressure passage 110 and at suitable times in the rotation of the shaft connect the low pressure passage with the passages 52 through the partition 3 which lead into the piston chambers, as shown, for example, in the position marked 123a in Figure 6.

From the foregoing description of an embodiment of this invention, it should be evident to those skilled in the art that various changes and 20 modifications might be made without departing from the spirit or scope of this invention as defined by the appended claims.

I claim:

1. In a mechanism of the class described, a substantially cylindrical casing, a member within said casing extending between the end walls thereof, a rotary shaft extending axially through said casing, means for eccentrically supporting said member from said shaft to produce a gyroscopic motion of said member on rotation of said shaft; an eccentrically mounted counterbalance for said member, and means for varying the amount of eccentricity of said member and simultaneously therewith varying the eccentricity 30 of said counterbalance to produce substantial balance in said mechanism.

2. In a mechanism of the class described, a substantially cylindrical casing, a shaft extending axially through said casing, a piston member within said casing and operatively connected to said shaft for eccentric movement on rotation of said shaft, means defining with said casing and member fluid chambers variable in capacity by angular movement of said shaft about its axis, and counter weights operatively associated with 40 said shaft at opposite sides of said piston member and having their centers of gravity eccentrically disposed relative to said shaft oppositely to the eccentricity of said member, and means for simultaneously varying the eccentricities of 50 said member and said weights.

3. In a mechanism of the class described, a substantially cylindrical casing, a rotary hollow shaft extending axially through said casing, a member within said casing, a rod extending through said shaft concentric therewith and having parallel face portions extending at an angle to its axis, elements from said member extending through openings in said shaft and bearing on 60 said face portions, and means actuatable to move said rod axially within said shaft thereby to move said elements axially and vary the eccentricity of said member relative to said shaft.

4. In a mechanism of the class described, a substantially cylindrical casing, a rotary hollow shaft extending axially through said casing, a disk member within said casing, a rod extending through said shaft concentric therewith and having parallel face portions extending at an angle to its axis, elements from said member extending 70 through openings in said shaft and bearing on said face portions, means actuatable to move said rod axially within said shaft thereby to move said elements axially and vary the eccentricity of 80 said member relative to said shaft, a ring ele-

ment within which said member is rotatably mounted, and means for preventing rotation of said ring member with said disk member and for causing orbital motion thereof by the eccentric motion of said disk member.

5. In a mechanism of the class described, a substantially cylindrical casing having closed end walls and a partition intermediate said walls, a shaft journaled axially of said casing and extending therethrough, an annular piston slidable between one of said end walls and said partition and connected to said shaft for a gyroscopic sliding movement on rotation of said shaft, a valve ring slidable between the other of said end walls and partition, means connecting said piston with said casing defining therewith chambers variable in capacity on angular motion of said shaft, said valve and partition having ports cooperating to admit fluid under pressure to said chambers on one side of said shaft, and to exhaust fluid from the chambers on the other side of said shaft, and means for preventing rotation of said piston and valve ring comprising a shaft journaled in said partition and having end crank portions journaled respectively in openings in said piston and 100 valve ring.

6. In a mechanism of the class described, a substantially cylindrical casing having closed end walls and a partition intermediate said walls, a shaft journaled axially of said casing and extending therethrough, an annular piston slidable between one of said end walls and said partition and connected to said shaft for a gyroscopic sliding movement on rotation of said shaft, means for varying the amplitude of said movement, a 110 valve ring slidable between the other of said end walls and said partition, means connecting said piston with said casing defining therewith chambers variable in capacity on angular motion of said shaft, said valve and partition having ports 115 cooperating to admit fluid under pressure to said chambers on one side of said shaft, and to exhaust fluid from the chambers on the other side of said shaft, and means for preventing rotation of said piston and valve ring comprising a shaft journaled in said partition and having end crank portions journaled respectively in openings in 120 said piston and valve ring, said piston crank portion having movable connection with said partition shaft to allow for variation in amplitude of 125 gyroscopic movement of said piston.

7. In combination, a wall member having ports for the passage of fluid under pressure, a second wall member spaced from said first member, a valve plate slidable between said wall members, admission and exhaust ports through said first mentioned wall member with which said second wall member ports may be selectively connected by movement of said valve plate, said first mentioned wall member having recesses opposite to the ports of said second wall member and said valve plate having openings therethrough establishing communication between said recesses and first mentioned wall member ports, thereby to equalize the pressure of said fluid on opposite 130 sides of said valve plate.

8. In a mechanism of the class described, a substantially cylindrical casing having transverse wall members, a shaft journaled axially of said casing and extending through said wall members, a member slidable between said wall members and connected to said shaft for gyroscopic sliding movement on rotation of said shaft, means for varying the amplitude of said movement, and means for preventing rotation of said gyroscopic 140

member with said shaft comprising a shaft journaled in one of said wall members and having a crank portion journaled in said rotary member, said crank portion having movable connection to its shaft to allow for variation in amplitude of gyratory motion of said slidale member.

9. In a mechanism of the class described, a substantially cylindrical casing having transverse wall members, a shaft journaled axially of said casing and extending through said wall members, a member slidale between said wall members and connected to said shaft for gyratory sliding move-

ment on rotation of said shaft, means for varying the amplitude of said movement, and means for preventing rotation of said gyratory member with said shaft comprising a shaft journaled in one of said wall members and having a crank portion journaled in said rotary member, said crank portion and its shaft having slidale tongue and groove connections with each other to allow for variation in amplitude of gyratory motion of said slidale member.
